(57) **CLAIM**

The ornamental design for a steam nozzle, as shown and described.

DESCRIPTION

This application incorporates by reference for all purposes the full disclosure of co-pending U.S. patent application Ser. No. 16/576,728, filed concurrently herewith, entitled “Nozzle Structure For Steaming Milk.”

FIG. 1 is a front perspective view of a steam nozzle showing the new design in accordance with a first embodiment;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof;

FIG. 8 is a front perspective view of a steam nozzle showing the new design in accordance with second embodiment;

FIG. 9 is a front elevation view thereof;

FIG. 10 is a rear elevation view thereof;

FIG. 11 is a right elevation plan view thereof;

FIG. 12 is a left elevation view thereof;

FIG. 13 is a top plan view thereof; and,

FIG. 14 is a bottom plan view thereof.

The broken lines in the drawings represent portions of the steam nozzle and form no part of the claimed design.
